UNITED STATES PATENT OFFICE.

JOHN C. BOYD, OF ST. LOUIS, MISSOURI.

LAST FOR USE IN FORMING AND LEVELING SOLES.

Application filed November 22, 1920. Serial No. 425,632.

To all whom it may concern:

Be it known that I, JOHN C. BOYD, a citizen of the United States, residing in the city of St. Louis and State of Missouri, have invented new and useful Improvements in Lasts for Use in Forming and Leveling Soles, of which the following is a specification.

This invention relates to the art of shoe making and has for its general object, an improvement in that class of machines which are used for forming and leveling the sole of the shoe.

In this class of machine a lower member called a last or foot has the partly finished shoe applied thereto and an upper member containing a male or leveling form, having a shape complementary to that of the last or foot is brought down upon the sole of the shoe under very great pressure. These machines not only shape and level the sole but the tacks and threads used in securing the outer sole to the upper and inner sole are supposed to be embedded thereby into the inner sole so as to make the upper surface of the latter practically smooth and free from projections. The last or foot on which the partly completed shoe is placed for the purpose of the above operation, is supposed to have a substantially flat upper surface. I have found in practice, however, that the last or foot of this machine will, on its upper side, frequently be higher along a longitudinal central line than at the sides or marginal portion thereof, so that when the male or leveling form is brought down upon the sole, the latter will be depressed at the center more than is necessary, and less pressure than is necessary to force the projecting ends of tacks, and the threads, into the inner sole will be exerted at the marginal portion of the latter.

It is the purpose, therefore, of my invention to insure that the marginal portion of the sole shall always receive the maximum of the pressure exerted by the male or leveling form, and to this end my invention consists in providing a flat marginal portion extending entirely around the upper surface of the foot or last and in forming a depression in the remaining portion of such upper surface, said depression starting at the inner confines of the marginal portion and extending to the longitudinal center of the last, where it may have a depth of one-thirty-second of an inch more or less. Thus

when the pressure is exerted by the leveling form on the sole of the shoe inserted on the last, the maximum of the pressure exerted will be borne by the flat marginal portion, the portion of the sole surrounded, so to speak, by this marginal portion yielding under pressure, as it is forced into the slight depression referred to. By so proceeding, I secure certainty in the finish of the shoe as regards the embedding of the points of tacks, and of the securing threads in the inner sole, and by thus insuring a smooth interior, greatly add to the comfort of the wearer while maintaining uniformity as respects this characteristic of the shoe. The uniformity of interior finish in the respects noted is especially important in its application to ladies' shoes, and it is for use in shaping and forming the soles of such shoes that my invention is particularly designed.

In the accompanying drawing, Figure 1 is a view in side elevation, illustrating a lady's shoe on a foot or last with an upper male or leveling form shown in compressing position thereon, the lower portion only of the leveling form being shown, and the means for operating the same being omitted;

Figure 2 is a section on the line 2--2 of Figure 1, and

Figure 3 is a top plan view of the foot or last, illustrating the flat marginal portion and the central longitudinal depression extending inward from the marginal portion, on the upper or tread surface of the last.

Referring now to the drawing, Figure 1 indicates a standard preferably formed integral with which is a last or foot 2 of the desired size and configuration of the style of shoe to be operated upon. As shown by Figure 3, the upper surface of this last is provided with a flat marginal portion 3 extending entirely around the last and with a central depressed portion 4 which starts at the inner confine of the flat portion 3 and extends to the longitudinal center of the last, the depth of the depression being substantially one-thirty-second of an inch. Owing to the shallowness of the depression, there is no sharp edge caused to exist along the inner margin of the flat portion 3 but if desired, this part of the surface of the last may be filed off or otherwise rounded or smoothed. The numeral 5 indicates the male or leveling form and the numeral 6, the shoe, the sole of which is to be leveled and shaped.

As will more clearly appear from Figure

2 of the drawing, when the leveling form 5 is brought down with great pressure upon the sole 7, the marginal portion of the inner sole 8 corresponding to the flat marginal portion 3 will be forced downward against this flat marginal portion and the projecting ends of any nails or tacks, and any protruding threads or knots will be firmly embedded in the said inner sole so that the marginal portion thereof will be relatively smooth and free from projections of any character.

For the sake of clearness in illustration, the bottom of the depression 4 in Figure 2, is shown as considerably removed from the under side of the inner sole 8. In practice, however, the depression in the surface of the last is so slight that the depression would actually be filled up and the requisite pressure applied to the central portion of the sole 20 in giving the necessary shape thereto. The operation of shaping and leveling the sole is well understood to those skilled in the art and in the practice of my invention no different operation is followed from that heretofore practiced, the only difference being in construction, and consisting in the provision of a depression in the upper surface of the last surrounded by a flat marginal portion, to insure of an adequate pressure being exerted on the corresponding marginal portion 30 of the inner sole.

While the invention is not limited to exact dimensions or proportions, I find that a flat marginal portion one-half inch in width and a central depression of a maximum depth of one-thirty-second of an inch, will usually answer all the purposes of the invention, irrespective of the length or width of the last.

I claim:

40 1. A last for use in leveling and shaping

the soles of shoes, having a tread provided with a shallow depression extending longitudinally of the last substantially from end to end thereof, and affording a smooth flat marginal portion entirely surrounding said depression, the surface of the depression and the surface of said marginal portion merging into each other in a manner to provide a substantially continuous tread surface free from an appreciable line or area demarking the 50 conjunction of the surfaces.

2. A last for use in leveling and shaping the soles of shoes, having its outer surface or tread provided with a flat marginal portion and a shallow depression extending longitudinally of the last from end to end thereof and surrounded by said flat portion, the wall of which depression being gradually inclined downwardly in all directions from the inner boundary of said marginal portion, the entire working surface of said tread being smooth and devoid of an abrupt edge or shoulder.

3. A last for use in leveling and shaping the soles of shoes, having a flat marginal portion on the outer or tread surface of the last surrounding a depression extending longitudinally of the last substantially from end to end thereof, the upper confines of said depression merging into the inner boundary of said marginal portion at such an angle as to prevent the formation of an abrupt sharp edge or ridge, and said depression being sufficiently shallow to permit the entire surface of the tread to be effective in leveling and shaping the sole.

In testimony whereof, I have hereunto set my hand:

JOHN C. BOYD,
